UNITED STATES PATENT OFFICE.

GEORGE A. MELLON, OF ST. LOUIS, MISSOURI.

SPRING BED-BOTTOM.

1,084,948.

Specification of Letters Patent. Patented Jan. 20, 1914.

Application filed February 27, 1913. Serial No. 750,997.

To all whom it may concern:

Be it known that I, GEORGE A. MELLON, a citizen of the United States of America, and a resident of the city of St. Louis and 5 State of Missouri, have invented certain new and useful Improvements in Spring Bed-Bottoms, of which the following is a full, clear, and exact description, reference being had to the accompanying drawings, 10 forming a part of this specification.

My invention relates to bed bottoms of the kind in which upright coil springs are utilized, and the invention has several objects, which may be set forth as follows: To 15 produce a spring bed bottom of a construction in which the top of the spring bed bottom is divided into two longitudinal sections, in either of which the springs may yield independently of the other section, in 20 order that when the sections are in service to support persons of unequal weight, a greater depression or displacement of the springs of one section will not be transmitted to the springs of the other section. 25 In my improvement, this object is attained by dividing the bed bottom at its surface in such manner that the springs of each of the sections are free of connection at their upper ends with the springs of the other section, 30 and all of them in the two sections are joined by suitable connecting means to end rails of the bed bottom frame common to both of the sections.

Figure I is a top or plan view of my 35 spring bed bottom, the transverse slats and bottom stay wires being omitted to avoid confusion in the illustration. Fig. II is a side elevation of the bed bottom. Fig. III is a perspective view of a portion of the 40 bed bottom frame. Fig. IV is an enlarged top or plan view of fragments of the top coils of two of the upright springs in a transverse row of said springs, and the hinge connection uniting said coils. Fig. 45 V is an enlarged cross section, taken on line V—V, Fig. IV.

In the drawings: 1 designates the end rails of the frame of my bed bottom, which 50 extend the entire width of said bed bottom. These end rails serve as supports for upright coil spring supporting members, comprising drop hangers 2, longitudinal rails 3, secured to said drop hangers, and transverse slats 4, attached to said longitudinal rails. The spring supporting frame 55 members mentioned, inclusive of the drop

hangers 2, are supported by the end rails 1, which serve to support the coil spring sections of my bed bottom.

The upright coil springs of my bed bottom are all similar in construction, and they are arranged in rows extending both longitudinally and transversely of the bed bottom, above and resting on the spring supporting frame suspended from the end rails 60 1. Inasmuch, however, as the coil spring structure is divided above its base into sections, I will, for the sake of clearness of description, designate the upright coil springs in one section A and the coil springs 65 in the other section *a*. These springs are all connected at their lower ends by crossing wires, as is usual in coil spring bed bottom structures, these wires and the springs being supported by the longitudinal 70 bars 3 and slats 4 of the bed bottom frame. 75

The upright coil springs A and *a* are connected to each other in both the longitudinal and transverse rows of such springs by longitudinal tie wires B, which are applied 80 to the top coils of said springs in a manner to be hereinafter explained; and the ends of these tie wires are connected to the end rails 1 of the bed bottom frame by helical tension springs G, with an object in 85 view that will be hereinafter made clear. By referring to Fig. I, it will be observed that the upright coil springs A and *a*, in longitudinal rows of said springs, adjoining each other at the transverse mid portion 90 of the bed bottom, are free of connection with each other, the longitudinal tie wires B' at this location being attached only to a single longitudinal row of upright coil springs, either A or *a*. The tie wires 95 B', therefore, constitute inner border wires for the sections of the bed bottom, in which the springs A and *a* exist, and which have no connection with each other, except through the end rails of the bed bottom 100 frame. The outer longitudinal rows of the upright coil springs A and *a* are attached to border strips or bars H, by any suitable means, such as wire loops fitted to the top coils of the springs, and united at their ends 105 to the end rails 1 by helical tension springs G'.

From the foregoing, it will be quite apparent that the spring sections of my bed bottom, comprising the upright coil springs 110 A and *a*, are entirely independent of each other above the bases of said springs; and,

consequently, the spring structure in each section may partake of separate movement when subjected to the weights of persons lying thereon, without the movement of the 5 springs in one section being communicated to the springs in the other section. Therefore, when my bed bottom is in service to support two persons of unequal weight lying above the two sections of the bed bottom, the 10 springs will yield in each section commensurate only to the weight imposed thereon, without the objectionable uneven depression of spring structure that occurs in the ordinary continuous spring structures of bed 15 bottoms when they are required to support persons of unequal weight.

I will next proceed with the description of the hinge sections for the top coils of the upright coil springs of my bed bottom, 20 which are, as previously stated, included in the longitudinal tie wires, and serve to join the upright springs, both longitudinally and transversely of the bed bottom. These connections are integral parts of the longitudinal tie wires, and each connection comprises kinks C, formed to extend laterally from spaced portions in the tie wire containing the connection, and in which the top coil of one of an adjoining pair of upright 25 coil springs is fitted. As illustrated in the drawings, these kinks extend beneath the coil they are fitted to, and then upwardly and over the coil. The remainder of the 30 connection is in the form of a loop comprising transverse members D, which extend laterally from the kinks C, return bends E, which receive the top coil of the second upright spring, and a U-shaped portion F, which extends backwardly from the return 35 bends E, beneath the top coils of the two springs, to and preferably beyond the top coil that is fitted in the kink C of the connection. It will be obvious that a connection made as described joins the top coils of 40 springs in a transverse row of my bed bottom in such manner as to permanently connect them; and, at the same time, permit freedom of vertical movement of each spring 45 relative to the other. It will also be obvious 50 that a series of such connections uniting the springs in the transverse rows and also extending along the longitudinal rows of springs serve to join the springs in the

longitudinal rows in a manner that will permit of their movement longitudinally 55 of the bed bottom when they are subjected to pressure. The upright springs may, therefore, be depressed or moved laterally, either transversely or longitudinally of the bed bottom, according to 60 pressure imposed against them, either uniformly or ununiformly; and, inasmuch as the tie wires in which the connections are included are united to the end rails of the bed bottom frame by the tension springs G, 65 the upright coil springs will always be returned to their normal positions when pressure against them is relieved.

I claim:

1. In a bed bottom, a frame comprising a 70 bottom structure, and a pair of end rails above said bottom structure, and two separate spring sections supported by said bottom structure; said spring sections being secured independently of each other to the 75 same end rails.
2. In a bed bottom, a frame comprising a bottom structure and a pair of end rails above said bottom structure, two sets of 80 spring sections comprising upright coil springs resting on said bottom structure, tie wires connecting the upper ends of said upright coil springs, the tie wires in each spring section being independent of the tie wires on the other spring section and being 85 connected to the same end rails.
3. In a bed bottom, a frame comprising a pair of end rails at the top of said frame, and two separate spring sections supported by said frame, the spring sections comprising 90 springs and means at their lower ends connecting the springs of one section with those of the other section, and means connecting the upper ends of the springs in both sections to the same end rails. 95
4. In a bed bottom, a frame comprising a pair of end rails and two separate spring sections supported by said frame, each of said spring sections comprising upright coil springs, tie wires connecting said upright 100 coil springs, and tension springs joining said tie wires to said end rails.

GEO. A. MELLON.

In the presence of—

MARY FAHEY,
A. J. McCauley.
